UNITED STATES PATENT OFFICE.

MORRIS H. HARTZELL, OF PHILADELPHIA, PENNSYLVANIA.

UMBRELLA RUNNER.

Application filed March 27, 1922. Serial No. 547,075.

To all whom it may concern:

Be it known that I, MORRIS H. HARTZELL, a citizen of the United States, residing at Philadelphia, in the county of Philadelphia and State of Pennsylvania, have invented 5 new and useful Improvements in Umbrella Runners, of which the following is a specification.

This invention relates to improvements in 10 umbrellas and has particular reference to means for holding an umbrella in closed position.

An object of the present invention is the provision of means which in addition to the 15 advantages above set forth will provide a quick and ready release of the holding means, the said holding means and releasing means being such as to especially adapt the invention for use in connection with self 20 opening umbrellas.

Another object of the invention is the provision of an umbrella holding and releasing device, which is simple in construction, positive in operation and which may be 25 manipulated with one hand.

With the above and other objects in view, the invention further includes the following novel features and details of construction, to be hereinafter more fully described, illustrated in the accompanying drawings and 30 pointed out in the appended claim.

In the drawings:

Figure 1 is a longitudinal sectional view 35 of a portion of the frame of an umbrella showing the latter in closed position.

Figure 2 is a similar view showing the ribs and runner released.

Figure 3 is a fragmentary section showing 40 the manner of depressing the runner engaging spring.

Figure 4 is a section on the line 4—4 of Figure 1.

Figure 5 is a detail view of the runner.

Figure 6 is a similar view of the sliding 45 rib retainer, the latter being partly broken away to show the slot.

Figure 7 is a fragmentary sectional view showing a modified form of the invention.

Figure 8 is a detail view of one end of the 50 runner shown in Figure 7.

Referring in detail to the drawings, wherein like characters of reference denote corresponding parts, the reference character 10 indicates the rod of an umbrella which 55 is shown as being of hollow tubular con-

struction and which carries at one end a handle or grip 11.

Mounted for sliding movement upon the rod 10 is a runner 12, which is adapted to have connected thereto braces 13 for connection with ribs 14. The runner 12 is of cylindrical formation and includes a restricted portion 15 which engages and slides on the rod 10, so that the said runner will be guided in its movement during the opening and closing of the umbrella.

Located within the rod 10 is a spring member 16, having one end positioned within an opening 17 provided in the rod 10 and its opposite end extending through a slot 18 and forming a latch or dog 19. The intermediate portion of the member 16 is provided with a lug 20 which bears against the inner wall of the rod 10.

The inner end of the restricted portion 15 of the sleeve 12 is provided with a shoulder which is adapted to be engaged by the latch 19 and in the operation of the invention shown in Figures 1 to 6 inclusive, this shoulder is formed by enlarging the inner 20 end of the runner and bending the extremity of this enlarged portion inward, as shown at 21, so that the latch 19 may enter this enlarged portion and engage the shoulder 25 to hold the runner against movement.

Also mounted for sliding movement upon the rod 10 is a sleeve 22 which is adapted to enter the enlarged portion formed on the inner end of the runner 12 and this sleeve is provided with a slot 23 for the passage of 30 the latch 19 so as to permit the latter to engage the shoulder 21. The sleeve is provided at its opposite end with an annular boss 24 to provide a gripping element for operating the sleeve. Surrounding the rod 10 and abutting the end of the grip or handle 11 is a thimble 25 which provides a stop for engagement by the boss 24 to limit the movement of the sleeve 22 in this direction. Extending from the sleeve intermediate its 35 ends is a cup-shaped flange 26 which is adapted to receive the inner end of the runner 12, being sufficiently spaced from the runner to provide for the reception of the tips or ends of the ribs 14.

The invention is especially designed for use in connection with a self opening umbrella and when the latter is closed, the parts will be in the position shown in Figure 1. In order to permit the umbrella to open, the 40

sleeve 22 is moved in a direction toward the handle 11 and as the dog 19 extends through the slot in this sleeve, the end wall of the slot will engage an inclined or cam surface 27 provided on the dog so that the latter will be depressed within the rod 10 and disengaged from the shoulder 19. This will permit of sliding movement of the runner 12 in a direction away from the handle 11 and as the ribs 14 have been released from the cup-shaped flange 26 by the sliding movement of the sleeve 22, the umbrella will be permitted to open.

When closing the umbrella, the sleeve 22 is again moved inward toward the handle 11 so as to depress the latch 19 and permit the runner to slide over the latch. The ribs are then gathered inward around the end of the runner and the sleeve 22 released, whereupon the action of the dog will cause the sleeve to move in a direction away from the handle and permit the said dog to again engage the shoulder 21.

In Figures 7 and 8, the construction of the invention is the same except that instead of forming the inner end of the runner 12 with the enlarged portion as shown in the preceding figures, this end of the runner is only sufficiently enlarged to receive the end of the sleeve. A slot 28 is provided in this end of the runner to receive the latch 19 and the latter is adapted to engage a shoulder 29 formed at the inner end of the slot 28. The

operation of this form of the invention is similar to that previously described. While the invention is adapted for use with self opening umbrellas, it is also capable of use with manually opened umbrellas.

The invention is susceptible of various changes in its form, proportions and minor details of construction and the right is herein reserved to make such changes as properly fall within the scope of the appended claim.

Having described the invention what is claimed is:—

An umbrella comprising in combination, ribs, a rod, a runner slideable upon the rod for controlling the ribs, a spring actuated member projecting through a slot in the rod for engagement with the runner to hold the umbrella in closed position, a sleeve slideable upon the rod within the runner and having an opening for the passage of the spring actuated member whereby the latter may be operated to release the runner, a cup-shaped member carried by and surrounding the sleeve in the rear of said slot, said cup-shaped member adapted to receive the ribs when the umbrella is in folded position, said sleeve rearwardly of said cup-shaped member having an annular boss forming a finger piece, and said sleeve being held adjacent the handle end of the umbrella by the spring actuated member at all times.

In testimony whereof I affix my signature.

MORRIS H. HARTZELL.
